T. P. Britt

A technical line drawing of a mechanical assembly, possibly a valve or fitting. The drawing shows a central vertical rod with a flange at the top and a handle or lever on the right side. Several callout numbers are present: '36' points to the top left; '37' points to a small circular detail on the left; '38' points to a small circular detail on the right; '39' points to the handle; and '42' points to the top right. The drawing is done in a simple, functional style with heavy lines.

UNITED STATES PATENT OFFICE.

FREDERICK E. PARSLOE, OF MILWAUKEE, WISCONSIN.

MACHINE FOR EXAMINING TEXTILES.

1,272,513.

Specification of Letters Patent.

Patented July 16, 1918.

Application filed November 26, 1917. Serial No. 203,997.

To all whom it may concern:

Be it known that I, FREDERICK E. PARSLOE, a citizen of the United States, and resident of Milwaukee, in the county of Milwaukee and State of Wisconsin, have invented certain new and useful Improvements in Machines for Examining Textiles; and I do hereby declare that the following is a full, clear, and exact description thereof.

10 My invention relates broadly to improvements in machines for examining textiles, such as woolens, cottons or silk cloths of any texture, and more particularly to an apparatus for unwinding, examining, measuring and refolding cloth, which will require only one operation.

To those skilled in the art to which this invention belongs it is well known that it is necessary to closely examine all cloth before it is cut up in order to determine whether or not it is in any way defective. The usual method of doing this is to unfold the fabric and drape it over a suitable bar or the like before a strong light, either 25 artificial or natural, this being customarily done by hand.

Therefore, it is the object of the present invention to accomplish this examination with a saving of time and labor, this being 30 readily accomplished in one machine constructed in the manner illustrated.

An object of the invention subsidiary to the principal object is to provide a novel arrangement for automatically folding the 35 cloth after the examination thereof, the speed of such folding operation being proportionate to the rapidity of the examination.

A still further object of a minor nature 40 is to provide a measuring instrument in connection with the other features whereby the amount of cloth examined can be accurately determined.

Another object is to provide means for 45 controlling the speed of operation of the parts which move the cloth into position for examination thereof.

Still another object is to provide a device whereby double folded cloth may be 50 spread to its full width before being disposed for its examination.

With these and other minor objects and 55 advantages in view the invention resides in the novel features of construction, combination and arrangement of parts which will be

hereinafter more particularly described and claimed, and shown in the drawings wherein:

Figure 1 represents a front elevational view of a machine constructed in accordance with my invention.

60 Fig. 2 is an end elevation, partly in section, of the machine illustrated in Fig. 1.

Fig. 3 is a plan view of this improved machine with certain of the elements removed for convenience in illustration.

65 Fig. 4 is a vertical transverse section taken on the plane of the line 4—4 of Fig. 1.

Fig. 5 is a detail vertical longitudinal section on the line 5—5 of Fig. 2, showing particularly the means for varying the speed of 70 operation of the cloth feeding means.

Fig. 6 is a detail sectional view taken on the line 6—6 of Fig. 2, and

75 Fig. 7 is a fragmentary elevational view of the means for adjusting the cloth examining member.

The invention comprises broadly a supporting frame of a suitable type, a cloth examining member pivotally mounted on said frame, means for moving the cloth over 80 said examining member, means for measuring the quantity of cloth so moved, and means for folding the examined cloth. All of these features of the invention will be independently described and their relation 85 to one another explained.

A supporting base may be of any suitable or convenient design, but that illustrated has been found to work advantageously. It comprises a pair of end frames 1, 90 each of which is constructed substantially of three angle bars arranged in the form of a triangle, one of the sides 2 of which rests upon the ground thereby disposing the apex of the triangle upwardly. The sides 3 of 95 the frames 1 are braced intermediate their ends by the bars 4, and the base bars 2 are connected with similar channeled bars 5 each serving to space the end frames apart, and at the same time holding them in rigid 100 relation.

The upper ends or apices of the frames are connected by trunnions 6 of a feed roll 7, said trunnions being journally mounted in suitable bearings carried by said end 105 frames. A textile examining member 8 is tiltably mounted on the supporting base by means of said trunnions 6, said examining member comprising a rectangular frame 9 preferably formed of angle bars which 110

carry a transparent plate 10 such as of glass. The opposite end bars of the frame each has a segmental plate 11 secured thereto, said plates being provided with alined openings for the reception of said trunnions 6.

The arcuate edges of the plates 11 are cut to provide rack teeth which mesh with the teeth of pinions 12 that are carried by a shaft 13 also journally mounted on the end frames 1. Also fixed on the shaft 13 is a ratchet wheel 14 with which a pawl 15 engages to prevent retrograde movement of the shaft. By this arrangement the examining member 8 may be tilted from a horizontal to a substantially vertical position or to any intermediate point and held thus. This movement is obviously effected by rotation of the shaft 13 in the proper direction which causes the segmental plates to shift 15 around their axis. The examining member being pivoted intermediate its ends and nearer one end than the other, the overbalanced portion thereof will tend to cause the shaft 13 to revolve in one direction, said 20 tendency being overcome by the pawl and ratchet arrangement.

The cloth to be examined is conveyed across the upper face of the transparent plate 10, this movement being facilitated 30 by a guide roller 16 journaled in suitable bearings carried by the upper end of the frame 9 of the member 8. This roller 16 is of course positioned transverse of the direction of the movement of the cloth, and at 35 the opposite end of the frame is similarly positioned a second guide roller 17, this roller being journally mounted in brackets 18. The freedom of movement of the roller 16 is controlled by a spring tension device 40 consisting of a wheel 19, a leaf spring 20 and a set screw 21 for adjusting the spring toward and away from the wheel. These parts are shown in Figs. 1, 2, and 4.

The brackets 18 also have a third guide 45 roller 22 carried thereby, said guide roller together with the roller 17 and the feed roll 7 coöperating to move the cloth from the upper edge of the frame 9 to a point beneath said frame where it can be operated upon 50 by the folding means to be hereinafter more particularly described.

A plurality of feed belts 23 are disposed around the feed roll 7 and the guide roller 22 as shown, the upper stretch being engaged by the guide roller 17. The lower stretches of the belts are engaged by tensioning devices, one of which is provided for each of the belts. These tensioning devices are mounted upon a shaft 24, the latter 55 in turn being carried by the segmental plates 11. Each device consists of a roller 25 for engagement with a belt 23, an arm 26 for pivoting said roller 25 to the shaft 24, and a coiled spring 27 engaged with said arm 26 60 for moving said roller toward the belt.

The feed roll 7 is revolved by any suitable power supplying machine, belted or otherwise connected with a pulley wheel 28, which is mounted on a stub shaft 29 carried by one of the end frames 1. The pulley wheel 70 28 is preferably clutched to the shaft to be controlled at the will of the operator of the machine as shown by the arrangement at 30 in Fig. 1. This clutch arrangement is actuated by the longitudinal sliding movement 75 of a foot bar 31 which is disposed on one of the brace bars 5 of the supporting base. It will be noted from Figs. 1 and 3 that the bar throughout its length is provided with a number of sets of projections 32 so that 80 the same may be actuated by the operator regardless of his position with respect to the ends of the machine. The movement of the bar 31 is obviously transmitted to the clutch mechanism by the intermediately pivoted lever 33 mounted upon a bracket 34 projecting from one of the end frames 1.

The speed of rotation of the feed roll 7 with respect to the pulley wheel 28 is readily varied by a suitable friction clutch comprising a pair of plain gear wheels 35 and 36 mounted respectively upon the shaft 29 and one of the trunnions 6 of the feed roll, and a shiftable friction gear 37. The gear 37 consists of a pair of circular plates 38 95 spaced apart to receive the gears 35 and 36, said plates being disposed on a stub shaft 39. The plates 38 are moved toward each other so as to tightly engage the friction wheels by an adjustable spring 40.

The shaft 39 being carried by a lever 41, the friction gear 37 is readily moved toward or away from either of the shafts 6 and 29. Such movement of the lever 41 is controlled by either one of a pair of bell cranks 42, one 105 of which is fixed to each end of a shaft 43 that extends longitudinally of the machine and across the front thereof. One end of each bell crank forms a handle while the other arm of one is linked as at 44 to the free end of the lever 41. Thus the speed of the feed roll can be controlled from either end of the machine.

The lever 41 is held against jarring out of its adjusted positions by the arrangement 115 shown in Fig. 6 which consists of a spring pressed plate 45 and a strip of non-metallic anti-slipping material 46, both of which are secured to the end frame by the bolts 47. The lever 41 is frictionally held between the 120 plate 45 and the strip 46.

Inasmuch as most woolens and suiting material are rolled or folded in double thickness, it must be unfolded before being examined, therefore I have provided a U-shaped 125 guide rod 48, the arms of which are pivotally mounted on the ends of brackets 49 which extend from the opposite ends of the frame 9. The ends of the arms which extend through said brackets 49 are threaded to re- 130

ceive nuts 50 whereby the rod may be held in adjusted positions with respect to the frame 9.

The cloth as it moves over the examining member 8 is measured by any conveniently formed measuring device such as that shown at 51. This device is geared to the feed roll 7 in any desirable manner, it being mounted on one of the end frames 1 adjacent one of 10 the trunnions 6 by means of a bracket 52.

After the cloth has been moved over the examining member by the feed roll and the feed belts it is folded upon the floor beneath the machine or upon a suitable table disposed thereunder. This folding device consists of an oscillatory plate 53 hinged to the shaft 13 and extending the full length of the machine. The plate is oscillated by means of a crank 54 connected with the same 20 by a pitman 55 as shown clearly in Fig. 1. The crank is connected with a shaft which is continuously revolved with the feed roll 7, it being connected therewith by a belt 56. Thus whenever the speed of rotation of the 25 feed roll is changed, the oscillation of the plate 53 will be proportionately varied.

The cloth as it passes over the feed roll is guided on to the oscillatory plate 53 and held against movement between said roll 30 and the shaft 13 by a plurality of guard strips 57, the opposite ends of which are disposed around the feed roll and shaft 13 respectively. Said feed roll is covered by any suitable friction material, such as fine sand- 35 paper or felt to prevent slippage of the cloth.

The operation of my invention with double folded cloth is as follows: The cloth examining frame is tilted to the convenience 40 of the operator or to permit the strongest light to be thrown through the transparent plate 10, such adjustment of the frame being accomplished as hereinbefore set forth. The bolt of cloth is then disposed adjacent 45 the guide 48 and the end of the strip disposed between the arms of said guide with the seam thereof resting in its apex. The portion of the cloth on each side of this fold will then lie on the arms of the guide, after 50 which the end of the strip of material may be moved upwardly, over the guide roller 16 and across the upper face of the member 8, after which it is directed around the guide roller 17 and on to the upper stretches of the 55 feed belts 23. Continuation of movement of the end of the strip of cloth to be examined disposes it on the feed roll 7 and oscillatory plate 53.

When the rotation of the feed roll 7 is 60 begun by actuation of the clutch 30 the cloth is moved across the transparent plate 10 to permit the light disposed beneath the same to shine through the cloth and thus permit detection of defects therein. Thus the cloth 65 is automatically unpackaged and after the

examination is complete is folded into a convenient and uniform pile. As some cloth can be examined much more rapidly than others, therefore the above described means for varying the speed of rotation of the feed 70 roll has been provided.

The simplicity of this machine is obvious from examination of the accompanying drawings and its effectiveness is believed to be thoroughly evident after an examination 75 of the drawings and the accompanying description.

I claim:—

1. In a machine of the class described comprising a supporting base, a material 80 examining member, a segmental plate fixed to the member and pivoted to the supporting base, gear teeth on the plate, a shaft carried by the supporting base, a pinion on the shaft and meshing with said gear teeth, and 85 means for rotating said shaft for tilting the member.

2. In a machine of the class described comprising a supporting base, a feed roll 90 journally mounted on said base, a material examining member pivoted on the axis of said feed roll, means for holding the member in adjusted tilted positions, and means for revolving the roll to move a strip of material over said member. 95

3. A machine of the class described comprising a supporting base, a feed roll journally mounted in said base, a material examining member pivoted on the axis of said feed roll and disposed immediately above 100 the same, a guide roller carried by the member at each side thereof, an additional guide roller disposed substantially parallel with one of the first guide rollers and spaced outwardly thereof, means for holding the member in adjusted tilted positions, and means for revolving the feed roll to move a strip of material around the single guide roller at one side of the examining member, over the outer face of the latter, between the pair 110 of guide rollers and around the feed roll between the same and the inner face of the examining member. 105

4. In a machine of the class described comprising a supporting base, a material 115 examining member, a plate fixed to the member and pivoted to said base whereby to permit said member to tilt, a guide roller carried by the member, a feed roll journally mounted on the base, a feed belt disposed 120 around the feed roll and guide roller, means for revolving the feed roll, and a tensioning device carried by the plate and engaged with said belt.

5. A machine of the class described comprising a supporting base, a material examining member mounted on the base, a guide roller carried by the member at one side thereof, a second guide roller disposed substantially parallel with the first and spaced 130

outwardly thereof, a feed roll journally mounted on the base, a plurality of feed belts disposed around the feed roll and the second guide roller and having one stretch 5 positioned to engage the first guide roller, and means for rotating the feed roll to move a strip of material over the examining member, between the guide rollers and over the feed belts.

10 6. A machine of the class described comprising a supporting base, a material examining member mounted on the base, a guide roller carried by the member at one side thereof, a feed roll journally mounted 15 on the base, a plurality of feed belts disposed around the feed roll and guide roller, a shaft connected with the examining member and disposed substantially parallel with the feed roll, a plurality of tensioning members 20 mounted on said shaft, one being in engagement with each of said feed belts, and means for revolving the feed roller.

7. A machine of the class described comprising a supporting base, a material examining member mounted on the base, a guide roller carried by the member at one side thereof, a feed roll journally mounted 25 on the base, a feed belt disposed around the

feed roll and guide roller, means for revolving the feed roll, and means for retaining the feed belt under tension, including an arm pivotally connected with the examining member, means for urging the arm toward the belt, and a roller on the free end of the arm for engagement with the belt. 30 35

8. A machine of the class described including a material feeding member, means for displaying material moved by said member, means for folding the material fed from said member and comprising a rod 40 disposed substantially parallel to the feeding member and spaced therefrom, an oscillatory plate pivoted at one end on said rod, means for oscillating said plate coincidently with the operation of the feeding member, and a plurality of guard strips 45 extending around the feeding member and connected with said rod to prevent material from passing between the feeding member and the rod. 50

In testimony that I claim the foregoing I have hereunto set my hand at Milwaukee, in county of Milwaukee and State of Wisconsin.

FREDERICK E. PARSLOE.
